DESIGN FOR A POSTAL SCALE

Alvah Bruce Jacobus, St. Johnsbury, Vt.

Application July 9, 1936, Serial No. 63,749

Term of patent 14 years

To all whom it may concern:

Be it known that I, Alvah B. Jacobus, a citizen of the United States, residing at St. Johnsbury, in the county of Caledonia and State of Vermont, have invented a new, original, and ornamental Design for a Postal Scale, of which the following is a specification, reference being had to the accompanying drawing, forming part thereof.

I claim:

The ornamental design for a postal scale, as shown.

ALVAH BRUCE JACOBUS.
